CLAIM

I claim the ornamental design for a tray, as shown and described.

DESCRIPTION

FIG. 1 is a perspective view of the tray;

FIG. 2 is a left side elevation view of the tray;

FIG. 3 is a right side elevation view of the tray;

FIG. 4 is a front elevation view of the tray;

FIG. 5 is a rear elevation view of the tray; and,

FIG. 6 is a top plan view of the tray.

Broken lines shown in the drawing views depict portions of the tray that form no part of the claimed design.
